UNITED STATES PATENT OFFICE.

SIDNEY H. HART, OF BROOKLYN, NEW YORK, ASSIGNOR TO THE E. H. HOTCHKISS COMPANY, OF NORWALK, CONNECTICUT, A CORPORATION OF CONNECTICUT.

STAPLING MACHINE.

Application filed August 12, 1920. Serial No. 403,004.

My invention relates to stapling machines such as are used for stapling sheets of paper together and it relates to that class of stapling machines in which the staples are supplied in strip form and in which the staples are individually severed from the strip. I have herein shown my invention embodied in the well known Hotchkiss stapling machine though it is to be understood that the invention is not limited to use in that particular machine.

In machines of the above type, wherein the staples are cut from a strip individually or as required for stapling several difficulties have been encountered. One is, that the cutters do not always cut a staple clean from the strip and the staple clogs the machine or else it is turned so that it is not presented to the paper or other material to which it is to be applied, in the proper position. In some cases the movable cutter or plunger becomes jammed and it is difficult to return it and to get the jammed staple out of the machine. In other cases the staple is driven down but it is twisted or turned and it fails to properly enter the paper or else it fails to enter in the desired position or angle. The above difficulties are due to the failure of the cutters to cut the staple clean from the strip or to cut it at the required position.

The difficulties referred to are almost certain to occur when the cutters become dull as they do after they have been used for a short time.

Furthermore, it has been difficult to use very thin stock for the staple strip. The present invention overcomes these difficulties. Its employment does not complicate the machine nor add materially to its cost, and there is nothing to get out of order. In my copending case Ser. No. 352,021, I showed and described a machine for the same general purpose in which stationary projections supported the projecting end staple during the cutting or shearing operation. My present invention is of the same general character but it is specifically different in that the supporting member for the projecting or endmost staple comprises a movable slide.

Another difficulty in former machines is the tendency to clog when the plunger is only partly driven down, and is then allowed to return and is then driven down a

second time. In such instances a staple is cut when the plunger is first forced down but as the stroke is not complete the staple is not driven into the stock but remains in the machine. Upon the return stroke of the plunger the staple strip is fed forwardly so that on the second downward stroke of the plunger another staple is cut and driven down on the first one and one or both staples clog the machine. In the present case the strip is not fed forwardly unless the preceding staple has been driven. If, therefore, the plunger is depressed only part way down and is then allowed to return, the staple strip is not at this operation fed forwardly and when the plunger is depressed again a new staple is not cut off but the previously cut staple is driven, so that the machine is cleared ready for the next operation. This result I accomplish by timing the feeding operation so that it occurs only when the plunger is driven all the way down, and missing a feed if the plunger is only partly depressed.

In the drawing forming part of this application,

Figure 1 is a vertical sectional view through a stapling machine embodying my invention,

Figure 2 is an enlarged sectional view showing the parts for operating and guiding the staples,

Figure 3 is a face view of the slide for supporting the endmost staple,

Figure 4 is a cross sectional view through the frame and showing the plunger and slide,

Figure 5 is a sectional view showing parts similar to Figure 2 in different positions,

Figure 6 is a detail view of the cam on the plunger and the part of the feeding device on which it acts,

Figure 7 is a horizontal sectional view showing the guide bar with a strip of staples in plan,

Figure 8 is a view showing parts similar to Figure 5 but in different positions,

Figure 9 is a sectional view through the plunger and slide, and

Figure 10 is a similar view taken at a different point.

I have shown herein a stapling machine having most of its parts corresponding to machines as heretofore made. It comprises a base 1 at one end of which there is an

anvil 2 of usual form and in the seat 3 of which the prongs of the staples strike. At the other end of the base there are upstanding ears 4 between which one end of the cutter bar 5 is pivoted on a pin 6. The frame 7 of the machine surrounds the top and sides of the cutter bar 5 and it is fixed to it by means of the pins 8 which pass through the frame and cutter bar, so that the former moves with the latter. At the sides, the frame is spaced from the cutter bar by the rails 9 which are interposed between the sides of the frame 7 and parts of the sides of the cutter bar 5, and these rails are engaged by the prongs 10 of the uncut strip 11 and they serve to support the strip. The forward edge 12 of the cutter bar forms one of the cutting members for cutting or shearing the staples from the strip. There is a plunger 13 operating in a guiding socket 14 in the frame 7 and it moves at right angles to the plane of the cutter bar 5. The lower edge 15 of this plunger forms the second cutting or shearing member, and it cooperates with the forward edge 12 of the cutter bar. The plunger 13 is forced downwardly by hand and its return is effected by means of the compression spring 16. A pawl plate 17 is pivoted at 18 and it is actuated by means of the cam plunger. The shape of the cam member 19 and the surface of the plate 17 with which it engages are modified as shown, to time the operations according to the requirements of the present device. The plate 17 carries a pawl 20 having a forked end 21 which straddles the longitudinal rib 22 of the staple strip 11 and the forks engage between the prongs 10 for the purpose of advancing the strip. There is a detent arm 23 pivoted on the pin 24 and it has a forked end 25 which also straddles the rib 22 and engages between the prongs 10, being held in contact with the strip by the spring 26. Each time the plunger 13 goes fully down the pawl plate 17 is rocked backwardly by the shoulder 17^a striking the top 17^b of the plate 17, and the forks 21 of the pawl are moved back a distance equal to the distance between two adjacent openings or slots in the staple strip. As the plunger 13 is returned by the spring 16 the cam block 19 rocks the pawl plate 17 in the opposite direction and the forks 21 move the staple strip forwardly. The detent 23 rests on the strip 11 and it is intended to prevent backward movement thereof. As the shoulder 17^a does not strike the top 17^b of the plate 17 until the plunger is near the bottom of its stroke the pawl 20 is not moved backwardly and therefore it cannot feed the staple strip forwardly unless the plunger is moved substantially to the bottom of its stroke. If, therefore, the

plunger is forced downwardly sufficiently to sever a staple but not sufficiently to drive it, the pawl 20 will miss a feeding operation. Upon a subsequent operation of the plunger the previously cut but undriven staple will be driven and the machine will be cleared ready for another operation. Thus, one staple is not driven down upon another.

The staple strip 11 is inserted at the back of the machine between the frame 7 and the cutter bar 5 with the prongs 10 straddling this cutter bar and the connecting piece 22 extending along the top of the cutter. Generally, the points of the prongs rest upon the side rails 9. The strip projects beyond the cutting edge 12 of the cutter bar so that one pair of prongs is beyond the cutting point and so that only the connecting piece 22 between the first and second pair of prongs is in the line of cutting. When the plunger 13 is forced downwardly its edge 15 cooperates with the edge 12 to cut or shear the projecting portion of the strip which then constitutes a staple. The latter is carried down by the bottom end of the plunger and is stapled through the paper in a manner well known in the art.

Thus far I have described no means for supporting the overhanging end of the strip to prevent bending and without some such means this end is bent down during the cutting or shearing operation, causing the troubles referred to above.

The device for supporting the overhanging end of the strip during the shearing operation consists of a sliding member which does not interfere with the driving of the staple. There is a vertical slot 28 in the frame member 7 which opens into the slot in which the plunger moves and it is preferably wider than the latter slot. A plate 29 slides in this slot 28. It comprises upper, forked ends 30 which straddle the projection 31 of the plunger; a cross piece 32, and the lower, forked ends 33, all movable in the slot 28. The forked, lower ends 33 have an opening 34 between them wide enough to admit the staple strip therethrough, whereas the lower ends have projections 35 directed toward each other to align with the prongs of the staple strip. The plate 29 is preferably arched slightly to press the frame and frictionally engage or hold in whatever vertical position it is placed. When the plunger is in its uppermost position the plate 29 is likewise in its uppermost position, the cross piece 32 lying in contact with the cam member 19. In this position of the parts the staple strip projects beyond the end of the cutter bar 5 and through the wider opening 34 of the forked ends 33. The prongs of the projecting staple of the strip rest against the rear surfaces of the members 35 of the plate 29. The operator strikes the hand knob 36 a blow to force the plunger down. During

the first part of the downward stroke of the plunger the plate 29 remains idle and as the cutting edge of the plunger strikes the top edge of the projecting staple strip it cooperates with the edge 12 of the cutter bar and severs the projecting portion of the strip to form a staple. The members 35 engage the rear edges of the projecting prongs 10 while the cutting or shearing operation takes place, so that the projecting portion of the strip can not bend downwardly and cause an irregular shearing action. The effect is the same as if the projecting end of the strip rested on a support. If, therefore, the shearing members are dull or if they do not hug closely together a clean shearing operation will be performed notwithstanding this. As the plunger completes the shearing operation, or as its lower end registers with the lower ends of the members 35 the upper, forked ends 30 of the plate 29 are struck by the hand knob 36 and from this moment to the end of the downward stroke the plate 29 and plunger move in unison. The members 35 therefore descend with the severed staple, preventing the latter from turning and jamming. At the end of the downward stroke of the plunger the severed staple will have been driven through the material to be stapled and the lower ends of the prongs will have been clenched upon the anvil 2.

When the pressure on the knob ceases, the spring 16 will return the plunger to its raised position. When the plunger first starts to move upwardly the plate 29 remains idle or in its lowermost position, held there by friction on the sides of the groove 28. When the cam projection 19 of the plunger strikes the cross piece 32 of the plate 29 the latter will then commence to move up with the plunger and by the time the latter reaches the end of its upward movement the plate 29 will have been raised sufficiently to bring the members 35 into position to support the prongs of the overhanging portion of the staple strip. The pawl 20 feeds the staple strip forwardly while the plate 29 is

moving upwardly, so that the leading end is advanced through the wider opening 34 in this plate. The feeding operation is completed in time for the members 35 to rise up behind the prongs of the projecting part of the strip. These operations are repeated over and over again.

The members 35 form a rigid backing for the prongs of the staple strip during the severing operation and they follow down with the severed staple to prevent the latter from turning during the driving. The sliding plate is a simple member to manufacture as it may be stamped or blanked from sheet metal at a low cost.

Having described my invention, what I claim is:

1. A stapling machine in which individual staples are cut from a strip comprising a frame, a cutter bar, means for advancing the staple strip over the cutter bar to project the end thereof beyond the cutter bar to be severed, a slide movable at right angles to the cutter bar for maintaining the projecting end of the staple strip in horizontal position during the cutting operation, and a plunger moving at right angles to said cutter bar and co-operating therewith to sever the staple, said frame having a raceway for guiding said plunger and having a separate raceway for guiding said slide.

2. A stapling machine in which individual staples are cut from a strip, comprising a frame, a cutter bar, means for advancing the staple strip over the cutter bar to project the end thereof beyond the cutter bar to sever it, a plunger moving at right angles to and co-operating with said cutter bar to sever the staple, and a slide for engaging the projecting staple, said slide lying against one face of the plunger and movable parallel therewith, said frame having a raceway for guiding the plunger and having a separate raceway for guiding said slide.

Signed at the city, county and State of New York, this 4th day of August, 1920.

SIDNEY H. HART.
